UNITED STATES PATENT OFFICE.

JAMES DELBERT BLAYNEY, OF EDMONTON, ALBERTA, CANADA.

ROTARY EXPLOSIVE-ENGINE.

1,005,074.

Specification of Letters Patent. Patented Apr. 28, 1914.

Application filed May 6, 1913. Serial No. 765,806.

To all whom it may concern:

Be it known that I, JAMES D. BLAYNEY, a citizen of the Dominion of Canada, and a resident of Edmonton, in the Province of Alberta and Dominion of Canada, have invented a new and Improved Rotary Explosive-Engine, of which the following is a full, clear, and exact description.

This invention relates to explosive engines of the rotary type, in which cylinders and reciprocating pistons are employed to produce the power impulses, the pistons and cylinders operating on the well-known four-cycle principle.

15 The invention has for one of its objects to improve and simplify the construction and operation of engines of this character, so that great power is obtainable, considering the size and weight, as well as smooth running, because of the equal distribution of applied power and the counterbalancing of the parts.

Another object is the provision of a rotary engine of the piston and cylinder type 25 wherein the power impulses are applied at a considerable radial distance from the axis of rotation, in order to obtain the maximum power.

An additional object is a novel arrangement of cylinders and crank chambers with a simple and effective system for admitting the fuel charges to the respective cylinders, the cylinders being so disposed as to be effectively cooled, and the admission and exhaust for each cylinder being controlled by a rotary valve.

With these objects in view, and others as will appear as the description proceeds, the invention comprises various novel features 40 of construction and arrangement of parts which will be more fully described herein-after and set forth with particularity in the claims appended hereto.

In the accompanying drawings, which illustrate one embodiment of the invention, and wherein similar reference characters are employed to designate corresponding parts throughout the several views, Figure 1 is a central section of the engine taken transversely to the axis of rotation and through the piston cylinder power units; Figs. 2 and 3 are sections through one of the power units on the lines 2-2 and 3-3 of Fig. 1; Fig. 4 is a section through the entire engine on the line 4-4 of Fig. 1; and Fig. 5 is a similar section on the line 5-5 of Fig. 1.

Referring to the drawings, 1 designates the shaft of the engine, which is suitably held stationary, as for instance, by bearings 2, and between these bearings is rotatably mounted the engine structure.

The engine embodies a plurality of power units A, each consisting of a cylinder 3 and a reciprocating piston 4, the pistons being of the "trunk" type, and connected by a connecting rod 5, with a crank wheel 6, which wheel is arranged within a crank casing 7. The head of each cylinder has an inlet port 8 and an outlet or exhaust port 9, which may open directly to the atmosphere, or into a suitable muffler, not shown, and for controlling these ports 8 and 9 a rotary disk valve 10 is arranged in the cylinder in contact with the inner surface of the head thereof. This valve has a port 11 which is adapted to register with the ports 8 and 9, respectively, on the suction and exhaust strokes of the piston 4. The disk valve 11 is fastened to the inner end of a stem or rotating shaft 12 passing through an opening 13 in the head of the cylinder to carry on its outer end a gear 14 that meshes with a driving gear 15, as clearly shown in Fig. 5. Each crank wheel 6 is mounted on a shaft 16 journaled in bearings 17 in the casing of the engine, and on the shaft 16 is a miter gear 18 which meshes with a miter gear 19 fastened to a shaft 20 that extends toward the head of the cylinder of the same power unit for the purpose of driving the inlet and exhaust valve thereof, since on the shaft 20 is mounted the gear 15 which meshes with the gear 14 of the valve. With this arrangement the cycle of operation of each power unit is carried out on the well-known four-cycle principle.

When the piston moves outwardly on the power stroke it rotates the crank wheel 6, and on the succeeding stroke the port in the valve 10 registers with the exhaust port 9, so that the exploded gases are expelled, and on the next stroke a charge of mixture is sucked in through the port 8 in the cylinder head, and port 11 in the valve. During the next stroke the charge is compressed and ignited at the proper time in the usual manner, the ignition devices not being shown.

The impulse resulting from the explosions in the various cylinders is utilized to impart rotary motion to the power units as a unitary structure. For this purpose the gear wheels 6 are provided with teeth 21 which

mesh with teeth 22 of a gear wheel 23 fixed on the shaft 1. This gear wheel is shown as twice the diameter of the crank gear wheels 6, and as a result each power unit will perform its complete cycle of operation during one rotation around the fixed gear 23. In other words, there will be one impulse imparted to the rotary structure during each rotation. In this regard the engine is in ultimate effect similar to a two-cycle engine, which gives a power impulse for each rotation of the shaft, but as regards the power units themselves, they operate on the four-cycle principle.

15 The gear 23 is inclosed in a central casing 24 which constitutes a mixture chamber into which the fuel mixture is admitted through a bore 25 in the shaft 1, said bore communicating with the gear casing 24 by a port

20 26. The mixture passes to the respective cylinders through the crank casing 7 and conduits 27. Each conduit 27 connects the cylinder of one unit with the crank case 7 of the next unit, and in this manner the comparatively short passages are required. The gear for driving the various valves is inclosed in a casing 28 which is separated from the mixture-containing gear casing 24 by a partition 29. On this partition are mounted 30 the bearings 30 for the intermediate shaft 20 of the valve gearing. By the particular disposition of the cylinders shown the rotative power is applied at a considerable radial distance from the axis of rotation, and the direction of the application of power is tangential, resulting in the maximum leverage or production of maximum power.

35 It will be noted that the cylinders are connected at 31 and 32 to the central gear casing 24, Fig. 1, and the crank gear casings 7, the intermediate portions of the cylinders being disconnected from these parts, and as a result air can freely circulate entirely around the cylinders, which, taken together 40 with the fact that the cylinders rotate in the atmosphere, causes an effective cooling of the heated parts.

45 While only four cylinders or power units have been shown, it is to be understood that

more of them may be employed. Furthermore, the crank wheels 6 may be made larger than those shown; for instance, the same size as the inner gear wheel 23, but in this case each power unit will impart a rotative impulse once in every two revolutions of the engine structure instead of one impulse for every revolution in the form of the invention shown. Instead of the crank wheel 13 being stationary and the rest of the engine rotatable, the said crank wheel may be mounted to rotate with the engine shaft while the power units are held stationary. In this arrangement the cylinders can be water cooled when such method of cooling is desirable.

Having thus described my invention, I claim as new and desire to secure by Letters Patent:

1. A rotary engine comprising a central casing, a fixed gear therein, means for admitting fuel mixture to the casing, a plurality of power units carried by the central casing and each consisting of a piston and cylinder and a crank casing communicating with the central casing, a fuel conduit between the crank casing of one unit and the cylinder of an adjacent unit, and a valve controlling each conduit.

2. A rotary engine comprising a central casing, a fixed gear therein, means for admitting fuel mixture to the casing, a plurality of power units carried by the central casing and each consisting of a piston and cylinder and a crank casing communicating with the central casing, a fuel conduit between the crank casing of one unit and the cylinder of an adjacent unit, and a rotary valve in each cylinder controlling the admission of fuel thereto and the exhaust of spent gases therefrom.

In testimony whereof I have signed my name to this specification in the presence of two subscribing witnesses.

JAMES DELBERT BLAYNEY.
